UNITED STATES PATENT OFFICE.

ADAM SCHEID, OF HARRISON, ASSIGNOR TO ROBERT ATHERTON, OF PATERSON, NEW JERSEY.

DOBBY FOR LOOMS.

SPECIFICATION forming part of Letters Patent No. 554,314, dated February 11, 1896.

Application filed September 14, 1895. Serial No. 562,491. (No model.)

To all whom it may concern:

Be it known that I, ADAM SCHEID, a citizen of the United States, residing in Harrison, Hudson county, and State of New Jersey, have 5 invented certain new and useful Improvements in Dobbies for Looms; and I do hereby declare the following to be a full, clear, and exact description of the invention, such as will enable others skilled in the art to which 10 it appertains to make and use the same, reference being had to the accompanying drawings, and to letters of reference marked thereon, which form a part of this specification.

My present invention is an improvement on 15 the dobbey covered by my application for Letters Patent filed June 20, 1895, and serially numbered 553,405. Its object is to provide an adjustable supporting-rod for the upper and lower hooked jacks of a dobbey, of simple and 20 durable construction, reliable in operation, and which may be easily and quickly adjusted.

The invention consists in the improved dobbey, its adjustable jack-supporting rod, and in the combination and arrangements of 25 the various parts thereof, substantially as will be hereinafter more fully described and finally embodied in the clauses of the claim.

Referring to the accompanying drawings, in which like letters of reference indicate corresponding parts in each of the several views, 30 Figure 1 is a side elevation of a dobbey provided with my improved jack-supporting rod; Fig. 2, an enlarged detail view of the same, illustrated in connection with a portion of its lifting-lever. Fig. 3 is a front elevation, and Fig. 4 a sectional view on line $x-x$ of Fig. 3, 35 illustrating a modified form of the supporting-rod.

In said drawings, a is the dobbey-frame; b , 40 the harness-lever, carrying the connector c , to the outer end of which are pivotally secured the upper and lower hooked jacks d and e , adapted to be engaged by the lifters f and g , respectively, and all of the usual and well-known construction.

The lifting-lever h , pivoted as at h' and 45 operated through pattern-chain k , is provided at or near its inner end with a vertically-arranged slot h^2 , in which rests the pin i^3 , projecting horizontally from the link i^5 . To said link is adjustably secured, by bolt and nut i^7 ,

the flattened lower portion i^3 of the supporting-rod i , which is for that purpose provided with an elongated slot i^4 , through which the tightening-bolt i^7 passes. The supporting-rod i is either round or flat and is provided with an upper and lower collar or lug i^1 and i^2 , adapted to support the upper and lower jacks, respectively. The link i^5 can be provided with projecting flanges i^6 , as shown in 60 Fig. 2, to obtain a more secure and firmer joint between the said link and the flattened portion i^3 of rod i , if so desired.

Should during the operation of the machine 65 the jack-supporting collars or lugs i^1 and i^2 partially wear off, the tightening nut and bolt i^7 is loosened, the rod raised up to the required height, and the bolt and nut again tightened. By this simple means the frequent changing 70 of the jack-supporting rods and their respective collars is fully avoided and the device thus rendered more durable and economical.

I do not intend to limit myself to the precise construction shown and described, as various alterations can be made without changing 75 the scope of my invention.

Having thus described my invention, what I claim as new, and desire to secure by Letters Patent, is—

1. A jack-supporting rod for a dobbey, 80 consisting of a rod having an upper and lower collar or lug, and provided at its lower end with a vertically-arranged slot, a link arranged on the slotted portion of said rod, a nut and bolt to adjustably secure said link 85 and rod together, and a pin projecting horizontally from said link, all said parts, substantially as and for the purposes described.

2. The lifting-lever, the pattern-surface, 90 the upper and lower hooked jack, the connector, and the rod having an upper and lower collar or lug to support the upper and lower jack respectively, said rod being provided at its lower end with a vertically-arranged slot, a link carried by the lifting-lever and arranged on the slotted portion of said rod, a 95 nut and bolt to adjustably secure said link and rod together, combined with the harness-lever joined with the connector, and with the lifters to operate the jacks, substantially as 100 described.

3. The lifting-lever, provided with a verti-

cally-arranged slot, the pattern-surface to operate the said lever, combined with the upper and lower hooked jacks, the connector, the harness-lever attached to the connector, 5 the lifters to engage and move the jacks, the rod to support the upper and lower hooked jacks, and provided at its lower end with a vertically-arranged slot, a link on the slotted portion of the rod and provided with a horizontally-arranged pin adapted to rest in the

slot of the lifting-lever, and a nut and bolt to adjustably secure said link and rod together all said parts substantially as described.

In testimony that I claim the foregoing I have hereunto set my hand this 4th day of 15 September, 1895.

ADAM SCHEID.
